UNITED STATES PATENT OFFICE.

EARL M. WITHERELL, OF DULUTH, MINNESOTA.

KNITTING-MACHINE NEEDLE.

1,418,345.

Specification of Letters Patent. Patented June 6, 1922.

Application filed March 1, 1921. Serial No. 448,811.

To all whom it may concern:

Be it known that I, EARL M. WITHERELL, a citizen of the United States, residing at Duluth, in the county of St. Louis and State 5 of Minnesota, have invented certain new and useful Improvements in Knitting-Machine Needles, of which the following is a specification, reference being had therein to the accompanying drawing.

10 This invention relates to knitting machines and has special reference to a novel form of needle for such machines and the manipulation of same.

The principal object is to produce a form 15 of needle which may be employed in cooperation with other common forms of needles in such a manner as to permit of the continuous knitting of fabric, such as hosiery or the like, embodying two or more different arrangements of stitches, for example 20 the combination of ribbed and flat stitching as found in hosiery.

Another object is that of providing a novel method of cooperatively engaging different sets of needles to permit of such continuous operation on a single machine during the changing of the stitch.

Other objects and advantages will appear in the further description of the invention.

30 In the accompanying drawing forming part of this application and in which like reference characters indicate like parts:

Figure 1 is a perspective view of a fragmental portion of a knitting machine needle 35 carrying dial and cylinder such as commonly used in the knitting of hosiery; and

Figure 2 is a perspective view of an improved form of spring barbed needle.

In hosiery knitting it is the usual method 40 to transfer the ribbed portions of hosiery to a different machine on which the article is completed in a different form of stitch, and the expense and annoyance connected therewith is well known to those versed in the art, and; while it is known that there are 45 some comparatively few machines that avoid this by accomplishing a continuous process on one machine, it is possible only at the expense of considerable time, due to the cumbersome and slow method of changing the 50 stitches from one end of a needle to the other and changing the horizontally disposed needles to vertically operative ones, which can only be accomplished when the machine is 55 run very slowly.

In my present invention the different sets of needles remain in the same angular relation to each other at all times and at a predetermined moment in the operation of the machine the stitches in the garment being 60 knitted are transferred from the horizontal to the vertical needles in the manner which I shall proceed to describe, it being understood that the angular relation of the different sets of needles may vary considerably 65 from that here illustrated.

1 represents the horizontally disposed needle carrying dial of a hosiery knitting machine which has formed in the upper face thereof radially disposed slots in which the 70 needles reciprocate, the upturned inner ends of the needles extend through the slots and are controlled by the usual arrangement of cams, not shown.

2 represents the upper end of the vertically disposed cylinder of the machine within the outer circumferential face of which are formed spaced grooves or channels in which the common vertically disposed needles 3 operate.

In the method, for example, of ordinarily producing a common ribbed and flat stitched sock, certain of the vertical needles 3 are held out of action and the stitches which are thus missed by the cylinder needles are carried on by the dial needles so that the garment is completed in the desired ribbed state. Then when the flat stitching is commenced all of those stitches carried on the dial needles are transferred to the cylinder needles 90 and the former thrown out of action unless employed in producing some other form of stitch, such as double stitching or the like, which it is not considered necessary to describe.

To accomplish this transfer of stitches I have illustrated two different forms of dial needles which have been successfully employed for the purpose, and it is to be understood that other forms may be resorted to without departing from the spirit 95 of this invention.

The dial needle 4, shown in Fig. 1 of the drawing, is composed of two identical halves permanently united only at their inner upturned ends 5, the two halves being normally held tightly together by their own resiliency. Substantially midway their ends the two halves are bulged outwardly laterally as at 6 forming an opening or hole 110

intermediate of the halves, and through which opening the vertical needle 3 may be upwardly thrust when the dial needle is so positioned that said opening properly registers above the cylinder needle. In the foremost upper walls of the hole thus formed are angularly shaped notches 7, which, when the needle 4 is thrust forwardly, engages the upper portion of the loop 8 of the stitch in the garment 9 and carries it forwardly so that when the needle 3 is extended upwardly into the hole it will occur directly within the loop and be surrounded thereby.

Now when the needle 4 is withdrawn to its normal position within the dial and the cylinder needle subsequently depressed, the latter will carry with it the stitch, having transferred it entirely from the dial needle, and in which position the knitting is continued, resulting in the ordinary flat stitching.

From the foregoing it is evident that this transfer of stitches may take place when the machine is operated at ordinary speed as there is but slight abnormal action in any of the working parts.

In Figure 2 of the drawing is shown a spring barbed needle 10 equipped so as to function in the same manner as the needle 4, it being double only for a portion of its length from the inner end outwardly, but is provided with a central opening 11 therein, the auxiliary portion 12 extending outwardly only slightly beyond the opening or hole where it is turned inwardly, made pointed as at 13, and the extreme end normally nested within the concaved recess

14 to afford unobstructed engagement with the thread being used.

When this needle is engaged by its co-operative cylinder needle in the act of transferring a stitch, the result is identical with that previously described, the free end of the auxiliary portion 12 readily yielding away from the body of the needle to permit of the separation of the two needles.

Having thus described my invention, what I claim and desire to secure by Letters Patent, is:

1. A bifurcated needle of the class described having the two parts thereof bulged outwardly at a point intermediate of its ends forming a resilient loop engaging and expanding means for the reception of another needle in transferring the loop from the bifurcated needle.

2. A bifurcated needle of the class described having the two parts thereof bulged outwardly at a point intermediate of its ends forming a resilient loop engaging and expanding means for the reception of another needle through said bulged portion, a thread engaging hook on the free end of one of the bifurcated portions, and a pointed inwardly turned extremity on the other portion adjacent the bulge and normally engaging the other bifurcated portion, substantially as described.

In testimony whereof I hereunto affix my signature in the presence of two witnesses.

EARL M. WITHERELL.
